RESISTANCE ADAPTER FOR THORIATED FILAMENT VALVES

Zed J. Aflee, Chicago, and Archie C. Hallock, Elmhurst, Ill., assignors to Dunlee Corp., Chicago, Ill., a corporation of Illinois

Application May 24, 1954, Serial No. 431,652

4 Claims. (Cl. 315—58)

The present invention relates to thermionic devices and more particularly to an improved construction of a thermionic valve such as used in the power supply circuit of an X-ray tube.

A majority of the rectified X-ray equipment in use today utilizes a four-valve, full-wave type bridge rectifying circuit. Heretofore the rectifier tubes or valves have been equipped with pure tungsten wire filaments. Recently there have been developed rectifier valves utilizing thoriated tungsten wire filaments which possess numerous advantages over valves utilizing a pure tungsten filament. Accordingly, it is highly desirable that, as the tungsten filament valves need to be replaced, they be replaced with valves of the thoriated filament type. However, the pure tungsten type filament is ordinarily operated at a higher nominal voltage than a thoriated tungsten type filament and, consequently, the thoriated tungsten valve cannot be substituted for a pure tungsten type valve without changing the settings of the circuit or otherwise compensating for the differences in operating voltage. It is difficult to effect a change in the settings of the circuit inasmuch as the usual circuitry makes no provision for individual adjustments to the rectifier tubes, but instead usually employs a common adjustment for all rectifier tubes.

Accordingly, it is an object of the present invention to provide a new and improved thoriated tungsten filament type valve having means whereby the valve can be readily installed in a circuit arranged for use with valves of the pure tungsten type.

More particularly, it is an object of the present invention to provide a construction of a thoriated tungsten filament type rectifier valve whereby the valve can be readily adapted for use either in a circuit designed for thoriated tungsten filament type valves or for valves of the pure tungsten filament type.

A specific object of the invention is to provide a thoriated tungsten filament type valve having means for readily connecting or disconnecting a resistor in series with the filament of the valve to adapt the valve for the circuit in which it is to be used.

Another object of the invention is to provide means for readily connecting an electrical device such as a resistor into the circuit of an electrical element of a thermionic device.

Other objects and advantages of the invention will become more apparent hereinafter.

In accordance with the illustrated embodiment of the invention, a thoriated tungsten filament type valve is provided with a tubular mounting base on one end and upon which base is mounted a pair of terminal lugs, one of which is connected to the filament of the tube and the other to a terminal member for connecting the tube into the bridge circuit of an X-ray tube rectifier. The base is adapted to have a wire resistor wrapped therearound with the opposite ends of the wire connected to the lugs thus to connect the resistor in series with the filament. Alternatively, the resistor wire may be removed and the

2

two lugs interconnected to connect the filament directly to the terminal. Thus the valve may be readily adapted to compensate the same for the circuit in which it is to be used.

5 For a more detailed description of the invention, reference is made to the accompanying drawings wherein:

Fig. 1 is a side elevation of a tube constructed in accordance with the invention;

10 Fig. 2 is a fragmentary view of the tube with the resistor wires unwrapped from the tube base;

Fig. 3 is a view similar to Fig. 1 with the resistor removed and the two lugs interconnected to connect the filament directly to the terminal;

15 Fig. 4 is an exploded, fragmentary view of the base member;

Fig. 5 is a sectional view taken along line 5—5 of Fig. 1; and

Fig. 6 is a sectional view taken along line 6—6 of Fig. 4.

20 The rectifier valve or tube 10 shown in the drawing comprises a sealed envelope 11 of suitable material such as glass, in which is mounted a tubular anode 12 and cooperating cathode unit 13. The envelope is shown as tubular in form and having reentrant necks 14 at the 25 opposite ends upon which the cathode and anode are supported in the conventional manner.

The cathode, as shown, comprises a helical support member 17 formed of relatively heavy conductive wire and an emissive portion comprising a long coil of thin, thoriated tungsten wire 18. The filament is connected to leads 19, 20 leading out through the pinch stem 21 at the cathode end of the tube.

Provided on the cathode end of the tube is a base member comprising a tubular sleeve 25 of insulating material 35 cemented to the envelope end by suitable cement indicated at 26. The base member is provided with an end cap 27 also of insulating material and secured to the sleeve 25 by suitable means such as screws 28. Suitable terminal means are provided on the base member for connecting the same into the receptacle provided therefor in the rectifying circuit. In the present instance the valve is illustrated with the base member provided with a screw type terminal member 29 which includes a metallic threaded portion 30 and a contact button 31 electrically insulated from the threaded portion 30 by an annular ring 32 of suitable electrical insulating material. As illustrated, the filament lead 20 is connected directly to the contact button 31. The other filament lead 19 is adapted to be connected to the threaded contact portion 30 through the means now to be described.

50 The sleeve 25 is formed with a circumferential groove 35 in its periphery. Mounted adjacent one edge of the groove 35 are a pair of contact means such as conventional terminal lugs 36, 37, each of which includes a lead receiving socket or collar and a leaf portion. The sleeve 55 25 is provided with radially spaced apart openings 40, 41 in which the lug collars of the lugs 36, 37, respectively, are loosely received. The filament lead 19 is connected to the collar of the lug 36, while the other lug 37 is connected from its collar portion by a lead 42 to the threaded portion 30 of the terminal 29 as illustrated in Fig. 6.

The leaf portions of each of the lugs 36, 37 lie juxtaposed the outer surface of the sleeve 25 and are provided with openings through which fastening screws 45, 46, respectively, may extend, the screws being threaded in suitable apertures provided in the sleeve. The leaf portions are of such size and the openings 40, 41 are so spaced that one of the terminal lugs, the lug 37 in the instance shown, can be swung from the spaced apart position such as shown in Fig. 1, to an overlapping posi-

tion such as shown in Fig. 3 with relation to the other terminal lug 36.

Referring to Fig. 1, with the terminal lugs spaced apart a resistance wire 50 may be connected at its opposite ends to each of the lugs by the screws 45, 46 and wound in a loop fashion in the groove 35 as indicated in Fig. 2. The end of the resistor loop may be secured in place by a screw 51, as most clearly shown in Fig. 4. It will be noted that doubling the resistor wire and winding it in a loop as shown is advantageous in that any desired length of wire may be easily mounted on the tube base by selecting the position of the screw 51.

In the event that it is desired to operate the tube without the resistor wire in its place, the screws 45, 46 and 51 may be unthreaded and the resistor wire 50 removed and the lug 37 thereafter swung to place the leaf portions of both lugs in juxtaposition over the opening for receiving the screw 45, whereafter the screw may be put back into place as shown in Fig. 3, effecting a direct electrical connection between the lugs 36, 37.

By reason of the construction provided, the valve tube may be easily and quickly adapted for use either in a circuit having settings for the pure tungsten type filaments or for circuits having settings for a thoriated type filament.

While the invention has been described in its relation to use with rectifier valves for X-ray equipment, it will be apparent that the invention may be utilized in connection with thermionic devices in general.

Having illustrated and described a preferred embodiment of the invention, it should be apparent to those skilled in the art that the invention permits of modification in arrangement and detail. I claim as my invention all such modifications as come within the true spirit and scope of the appended claims.

We claim:

1. A thermionic device comprising an envelope, a filament in said envelope, a base member of electrical insulating material on said envelope and supporting a pair of terminals adapted to be connected to a source of electrical energy, and circuit means connecting said filament to said terminals including a pair of lug means mounted on said base member in electrically insulated relation and a resistor element removably connected between said lug means in series relation to said filament, at least one of said lug means being movable into contact with the other of said lug means to permit direct connection of said filament to said terminals upon disconnection of said resistor element from said lug means.

2. A thermionic device comprising an envelope, a filament in said envelope, a lead for said filament extending outwardly of one end of said envelope, a base member for said device including a sleeve of electrical insulating material mounted on said envelope end and terminal means for connection of the device to a source of electrical energy, a first terminal lug including a leaf portion juxtaposed the outer surface of said sleeve and a lead receiving socket means cooperatively received within an opening extending through the wall of said sleeve, screw means cooperatively received in said sleeve engaging said leaf portion for securing the same to said sleeve, a second terminal lug including a leaf portion juxtaposed the outer surface of said sleeve and a lead receiving socket means cooperatively received within a second opening extending through the wall of said sleeve, said second terminal lug being swingable about the axis of said second opening, said second opening being spaced from said

10 aforementioned screw means by such distance that said second terminal lug leaf portion can be swung into electrical contacting engagement with said first terminal lug leaf portion, said aforementioned screw means being adapted to engage said second terminal lug leaf portion to secure the same in contact with said first terminal lug, said second terminal lug being swingable to a second position in noncontacting relation to said first terminal lug, second screw means cooperatively received in said sleeve for securing said second terminal lug in said second position, one of said filament leads being connected to one of said terminal means, a third lead connecting another of said terminal means to one of said terminal lugs, the other of said filament leads being connected to the other of said terminal lugs, whereby said filament is connected relatively directly to said terminal means when said second terminal lug is in said electrical contacting engagement with said first terminal lug, said first and second screw means being adapted to secure the opposite ends 20 of a resistor element to the respective terminal lugs when said second terminal lug is in the second position thereof whereby to connect said resistor element in series with said filament.

25 3. A thermionic device comprising an envelope, a filament in said envelope, a base member of electrical insulating material on said envelope and supporting a pair of terminals adapted to be connected to a source of electrical energy, and circuit means connecting said filament to said terminals including a pair of contact means mounted on said base member in electrically insulated relation and a resistor element connected between said contact means in series relation to said filament, at least one of said contact means being movable into contact with the other of said contact means to permit direct connection 30 of said filament to said terminals.

35 4. A thermionic device comprising an envelope, a filament in said envelope, a base member including a sleeve of insulating material secured to one end of said envelope, a pair of terminal means on said base member for connecting said device to a source of electrical energy, a pair of contact means mounted on said base in electrically insulated relation, at least one of said contact means being movable into and out of contact with the other, circuit means connecting one side of said filament to one of said contact means, circuit means connecting the other of said contact means to one of said terminal means, circuit means connecting the other end of said filament to the other of said terminal means, and a resistor element comprising an elongate wire wound about the periphery of said sleeve, one end of said wire being electrically connected to one of said contact means and the other end of said wire being electrically connected to the other of said contact means, whereby when said contact means are out of contact with one another said resistor wire is connected in series with said filament and when said movable contact means is moved into contact with the other contact means said filament will be electrically connected directly to said terminal means.
